COMBINED PUSH PLATE AND LETTER DROP
FOR FULL-VISION DOORS

Lewis M. Sanders, Chicago, Ill.

Application December 31, 1947, Serial No. 795,039

3 Claims. (Cl. 189—46)

1

This invention relates to improvements in a combined push plate and letter drop for full-vision doors of the type disclosed in my copending application Serial No. 696,652 filed September 13, 1946.

Full-vision doors of the type disclosed in my copending application embody a door and door frame fabricated from metal to provide a complete unit suitable for installation within a building. Briefly, the door is preferably constructed of hollow extruded sections of light-weight metal, such as aluminum to provide top, bottom and side rail members welded together at their ends to form a relatively strong construction suitable to receive and support a rectangular-shaped plate glass panel. The door frame comprises a top transverse member and a pair of upright post members of angle iron section welded together at their ends to provide a jam wall and abutment wall for the door. A threshold plate is welded or otherwise secured to the lower ends of the side post members. To provide a full-vision door construction, the abutment wall provided on the top transverse member and the upright post members extends inwardly the full width of the top and side rail members of the door. It is thus necessary to secure a push plate to the inner edge of one of the side rails to project inwardly from the inner edge of the adjacent abutment wall of the door frame.

The present invention contemplates the provision of a combined push plate and letter drop for the type of door illustrated in the above mentioned pending application, and has for an object the provision of a structure of this type embodying inner and outer frame members mounted on opposite sides of a plate glass panel and secured to the inner side of an adjacent side rail of the door. The inner and outer frame members are formed with elongated apertures which are adapted to normally be closed by means of covered plates hingedly connected at their upper ends to their respective frame members. The cover plate adjacent the abutment flange of the door frame is formed with raised portions or impressions defining the word "push"; while the other cover plate is formed with impressions or raised portions defining the word "pull." When the inner and outer frame members are mounted upon the side rail of a door, the inner and outer cover plates are in registry with the rectangular opening formed in the plate glass panel of the door. By providing a letter drop in the push plate, the letter drop is at a convenient height for the insertion of mail through the door and is concealed from the public view.

2

This invention further contemplates the provision of a combined push plate and letter drop embodying a lock mechanism for locking the door against pivotal movement relative to the door frame.

This invention further contemplates the provision of a combined push plate and letter drop which is relatively inexpensive to manufacture and install and which does not detract from the full vision or appearance of the door.

This invention embodies other novel features, details of construction and arrangement of parts which are hereinafter set forth in the specification and claims, and illustrated in the accompanying drawings, wherein:

Fig. 1 is a front elevational view showing a combined push plate and letter drop mounted on the side rail of the door which, in turn, is hingedly mounted within a door frame.

Fig. 2 is a rear elevational view of same.

Fig. 3 is an enlarged detail rear elevational view showing the combined push plate and letter drop secured on the side rail of the door.

Fig. 4 is a detail sectional view taken along the line 4—4 of Fig. 1.

Fig. 5 is a transverse sectional view taken along the line 5—5 of Fig. 1.

Fig. 6 is a detail sectional view taken along the line 6—6 of Fig. 2.

Fig. 7 is a front elevational view illustrating a modified form of the combined push plate and letter drop.

Fig. 8 is a side elevational view of same.

Fig. 9 is a vertical sectional view taken along the line 9—9 of Fig. 7.

Fig. 10 is a transverse sectional view taken along the line 10—10 of Fig. 7.

Referring now to the drawings for a better understanding of this invention, the single door and frame construction is shown as comprising a door which is generally indicated at 11 and a frame which is generally indicated at 10. The door 11 comprises a top rail 12, a bottom rail 13 and side rails 14—14 which are preferably formed of hollow extruded metallic sections and welded together at their ends to form a rigid integral door structure capable of supporting a panel 16 formed of plate glass or other material. The panel 16 is secured in position between opposite faces of the rail members by means of molding strips 17 and 18 which, in turn, are secured to the inner faces of the door members 12, 13 and 14 by means of screws 19. A resilient gasket 21 is provided to enclose the marginal edge of the panel 16. It will be noted that the door 11 as shown and described presents the same appear-

ance from either side thereof and is therefore capable of being hingedly connected from either side rail 14 thereof and with either side of the door positioned for abutting engagement with a door frame.

The door frame 10 is shown as comprising a top transverse member 22, upright side post members 23-23, and a threshold or anchor plate 24 which are formed of metal and welded together at their ends to provide a rigid integral structure. As illustrated in Figs. 1 through 6, the frame members 22 and 23 are angle iron shape in cross section to provide an abutment wall 26 and a jam wall 27 for the door 11. In order to provide a neat finished appearance and to meet the desired structural requirements, the abutment wall 26 and jam wall 27 are formed to substantially enclose the adjacent faces of the door rails 12 and 14. A dovetail groove 28 is formed in the abutment wall 26 of the frame members 22 and 23 to receive a resilient weather strip 29 formed of felt, rubber or the like.

The door 11 is pivotally connected to the door frame 10 by means of a hinge 37 which preferably extends throughout the length of the door and with its two hinge arms 32 and 33 interposed between the inner face of the jam wall 27 of a post member 23 and the adjacent face of the side rail 14. The arms 32 and 33 of the hinge are secured to a side rail 14 and post 23, respectively, by means of screws 34.

It will be noted that the hinge 37 may be inserted between the side rail 14 and post 23 at either side of the frame depending upon whether it is desired to open the door to the left or to the right. It will also be noted that the door frame 10 may be positioned to permit the door 11 to swing either inwardly or outwardly relative to the interior of a room.

The combined push plate and letter drop is shown as comprising an outer frame 41 and an inner frame 42 which are secured in spaced parallel relation on opposite sides of the plate glass panel 16 to the inner side wall of a side rail 14 by means of screws 19. While the frame members 41 and 42 may be formed of any suitable material, they are preferably formed of steel or aluminum and provided with a suitable finish on their outer surfaces. The frame members 41 and 42 are secured to each other by means of a plurality of screws 43 which extend through the inner frame member for engagement in threaded apertures 44 formed in the outer frame member 41.

The frame members 41 and 42 are formed with elongated apertures 46 and 47, respectively, which are normally closed by means of a front cover push plate 48 and inner cover pull plate 49, respectively. As illustrated in Fig. 4, the upper end of the push plate 48 is pivotally connected at 51 to the upper end of the outer frame member 41. As illustrated in Fig. 5, the outer surface of the push cover plate 48 is flush with the outer surface of the frame member 41 to present a smooth unbroken appearance. The push plate 48 is also formed with depressions or raised surfaces 52 to define the word "push." If desired, the impressions or raised portions 52 may be of a different color than the adjacent surfaces. The upper end of the inner cover plate 49 is pivotally connected at 53 to the inner frame member 42, and has its outer surface formed with impressions or raised surfaces 54 defining the word "pull." The outer surface of the cover plate 49 is preferably formed

flush with the outer surface of the inner plate 42 to present a smooth uninterrupted surface. It will be noted that the cover plates 48 and 49 are hinged for pivotal movement in opposite directions and that they are normally disposed in closed position within their respective apertures 46 and 47 by gravity. If desired, a suitable spring clip 56 may be provided on the free end of the push cover plate 48 for engagement in a recess 57 formed in the frame member 41. The spring clip 56 would act to yieldably resist outward pivotal movement with the push cover plate 48. If desired, a spring member 58 may be provided on the free end of the inner cover plate 49 to yieldably resist opening movement of the cover plate. An opening 59 is formed in the plate glass panel 16 to register with the openings 46 and 47 formed in the frame members 41 and 42, respectively. A suitable handle 61 is secured to the side rail 14 adjacent the inner frame member 42.

To insert mail through the letter drop, the outer push plate 48 is pivoted outwardly and upwardly, the mail is then inserted through the openings 46 and 59 and against the inner cover plate 49 which is thus caused to pivot upwardly to permit the mail to pass through the opening 47 formed in the inner frame member 42. After the mail has been inserted through the letter drop, cover plates 48 and 49 will swing downwardly by gravity to their closed positions within their respective apertures 46 and 47.

Referring now more particularly to Figs. 7 to 10 in the drawings, a modified form of combined push plate and letter drop is shown as comprising an outer frame member 66 and an inner frame member 67 which are adapted to be secured to the inner face of a door rail and against opposite faces of the panel 16 by means of suitable screws passing through apertures 68.

The inner and outer frame members in this form of the invention may be constructed from extruded sheets and sections brazed or welded together, or they may be formed from stampings brazed or welded together. As the inner and outer frame members are formed of similar parts, only the outer frame member will be herein described, but corresponding reference numerals followed by the letter "a" will be applied to the inner frame member 67. The outer frame member 66 is shown as comprising a pair of angle plates 71 and 72 secured in spaced parallel relation to a pair of angle clips 73 and 74 and a pair of channel members 76 and 77. A spacing plate 78 is secured to the angle clip 74 and channel member 77 between the angle plates 71 and 72.

A cover plate 79 is pivotally connected on a hinge pin 81 provided at the upper end of the frame member 66. The cover plate 79 is adapted to present a smooth flush appearance with the front faces of the angle members 71 and 72 and to cover the aperture 82 defined in the outer frame member by the angle members 71 and 72, angle clip 74 and channel member 76. The inner and outer frame members 66 and 67 are secured against opposite sides of the panel 16 by means of bolts or screws 83 passing through apertures formed in the channel members 76 and 77. A lock chamber 84 is provided between the lower ends of the frame members 66 and 67 to receive a suitable lock mechanism 86. The lock mechanism 86 is provided with a suitable locking bolt (not shown) to extend through a door rail 11 into an aperture (not shown) formed in the jam wall 27 of a post member 10. The cover plates

79 and 79a are formed with impressions or raised portions 87 defining the words "push" and "pull," respectively.

It will be noted that the modified form of this invention, as illustrated in Figs. 7 to 10, inclusive, may be inexpensively fabricated from stampings or extruded members, brazed, welded or otherwise secured together to form a lightweight, rigid structure. It will further be noted that this form of combined push plate and letter drop may be positioned at either side of a door as the inner and outer frame members are of similar construction.

While this invention has been shown in but two forms, it is obvious to those skilled in the art that it is not so limited but is susceptible of various changes and modifications without departing from the spirit and scope of the claimed invention.

I claim as my invention:

1. A door structure comprising a top rail, a bottom rail, and side rails, said rails being formed of hollow extruded metal welded together at their ends to define a panel aperture, a plate glass panel mounted in said panel aperture, said panel having an opening therein adjacent the medial portion of one of said side rails, a metallic inner frame member, a metallic outer frame member, means to secure adjacent sides of said inner and outer frame members in cantilever fashion to the medial portion of the side rail adjacent said opening and on opposite sides of said panel, said outer frame member being disposed on said side rail to serve as a push plate in opening the door, each of said frame members being formed with an elongated vertically disposed letter slot for registry with the opening in said panel, each of said frame members being provided with a cover plate to close its respective letter slot.

2. A door structure comprising a top rail, a bottom rail, and side rails, said rails being formed of hollow extruded metal welded together at their ends to define a panel aperture, a plate glass panel mounted in said panel aperture, said panel having an opening therein adjacent the medial portion of one of said side rails, a metallic inner frame member, a metallic outer frame member, means to secure adjacent sides of said inner and outer frame members in cantilever fashion to the medial portion of the side rail adjacent said opening and on opposite sides of said panel, said outer frame member being disposed on said side rail to serve as a push plate in opening the door, each of said frame members being formed with an elongated vertically disposed letter slot for registry with the opening in said panel, each of said frame members being provided with a cover plate to close its respective letter slot.

opening and on opposite sides of said panel, said outer frame member being disposed on said side rail to serve as a push plate in opening the door, means disposed within said opening to secure said frame members against relative movement, each of said frame members being formed with an elongated vertically disposed letter slot for registry with the opening in said panel, each of said frame members being provided with a cover plate to close its respective letter slot.

3. A door structure comprising a top rail, a bottom rail, and side rails, said rails being formed of hollow extruded metal welded together at their ends to define a panel aperture, a plate glass panel mounted in said panel aperture, said panel having an opening therein adjacent the medial portion of one of said side rails, a metallic inner frame member, a metallic outer frame member, means to secure adjacent sides of said inner and outer frame members in cantilever fashion to the medial portion of the side rail adjacent said opening and on opposite sides of said panel, said outer frame member being disposed on said side rail to serve as a push plate in opening the door, means disposed within said opening to secure said frame members against relative movement, each of said frame members being formed with an elongated vertically disposed letter slot for registry with the opening in said panel, each of said frame members being provided with a cover plate to close its respective letter slot, the outer surfaces of said cover plates being flush with the outer surfaces of their respective frame members, said cover plates being hinged at their upper ends to their respective frame members and marked to indicate the direction of movement of the door.

LEWIS M. SANDERS.
